[57] ABSTRACT

A rotary dental burnisher for use in a conventional dental hand piece comprising a shank portion tapering down to and connected to a fluted burnishing head having a plurality of polished, rounded, elongated, ridges.

2 Claims, 4 Drawing Figures

PATENTED MAR 25 1975

FIG. 1

FIG. 3

FIG. 2

FIG. 4

ROTARY BURNISHERS

BACKGROUND INVENTION

In the dental arts there is a definite need for tools and methods to produce a smooth polished surface on exposed metal surfaces such as gold dental castings utilized to restore lost tooth structure. At present these smooth polished surfaces are produced with abrasives which are rubbed and worked against the gold surface with a tool. The typical prior art procedure for polishing gold comprises several steps. Irregular surfaces on the rough casting are ground off with a coarse abrasive wheel. Surfaces on the top of the casting (occlusal) are then ground into good matching shapes or good occlusion. Deeper parts are accented with steel or carbide burs and mounted stones. This leaves a shiny surface which is scratched and cut and therefore not too desirable. Next, the surfaces are semi-finished with an abrasive material contained in rubber. This is applied with a rubber wheel. Finally, a cloth wheel is used to produce a high shine by polishing with tripoli and gold rouge.

The problem with this approach is that the abrasive usually cannot be properly worked to smooth out the cut and scratched surface. The rubber points and wheels which are used in dental handpieces are totally inadequate to reach the small tight areas which have been accentuated or scored by the steel and carbide burs and mounted stones. The result is that the higher surfaces tend to be ground away without achieving progress toward polishing the deep areas. Thus, the good occlusion can be destroyed without really accomplishing an adequate polish. In fact, in the prior art this has constituted such a problem that the polishing process may consume 90 percent of the time required to finish and polish a crown or bridge gold restoration. My invention as described below provides a tool which shortens this time considerably by burnishing the surface rather than scoring it with abrasives.

SUMMARY OF THE INVENTION

My invention contemplates a rotary burnisher which may be produced in a variety of different sizes and shapes. It has been found that a burnisher designed according to the principles of my invention produces the desired polished finish in one or two minutes without removing any gold from the restoration. In this way, deep occlusal anatomy can be established to an extent heretofore impossible. A polish far superior than the prior art results and the good occlusion established in the rough finishing is not destroyed. To accomplish this end my invention contemplates a small burnishing head at the tip of a shank which shank is carried in a conventional dental handpiece. The burnishing head is formed with a series of bumps or irregularities in a fluted pattern which irregularities are carefully polished and smoothed. No cutting edges are present and no abrasives are required. Instead the tool operates by a slight hammering and friction process which smoothes the surface. Different shapes of burnishers are demonstrated designed to reach different surface contours. Thus, it may be seen that it is an object of my invention to provide an improved tool for polishing gold dental castings. Further objects and advantages will become apparent from the following description and drawings. 65

BRIEF DESCRIPTION OF THE DRAWINGS

FIG. 1 and FIG. 2 comprise respectively top and side views of one embodiment of my invention.

5 FIG. 3 and FIG. 4 comprise respectively top and side views of a second embodiment of my invention.

DESCRIPTION OF THE PREFERRED EMBODIMENT

10 Referring simultaneously to FIGS. 1 and 2 it may be seen that the burnishing tool of my invention is mounted at the end of a tapered shaft 10 and comprises a generally oval shaped head 12. Head 12 is provided, in the preferred embodiment shown, with eight 15 rounded ridges or flutes 14 with indentations 16 therebetween. The flutes 14 are carefully smoothed and polished so that no cutting edges are present. Head 12 may be formed from a suitable hardened steel or any other metal appropriate to the polishing task involved. Each 20 of the flutes 14 on head 12 curves from a point underneath head 12 near the shank 10 up around the circumference of head 12 and back in toward the end of the tool. The shape of head 12 is chosen primarily to provide a shape similar to a cutting bur so that the polishing head 12 fits evenly into the basic contours formed by the cutting bur. Since head 12 operates by a combination process of hammering and rubbing no abrasives are necessary and the gold casting is therefore not cut or scored as in the prior art. Although eight flutes are 25 shown in the preferred embodiment, any number can be conveniently used. The most important aspect of the design of the invention is that the flutes comprise rounded and polished bumps so that they do not cut or scratch on their own.

30 35 A second embodiment is shown in FIGS. 3 and 4. In the embodiment of FIGS. 3 and 4 a shank 20 supports a head 22 having several flutes 24 thereon. These flutes, like those in FIGS. 1 and 2 are rounded and polished to a high degree and are curved back under to 35 toward the shank 20. However, the top of head 22 is brought to a more distinct point so as to permit reaching into deep areas to accomplish the polishing function. In reality, the heads are, of course, very much 40 smaller than shown. The shape of heads 12 and 22 are 45 intended to show two arrangements which may be used. Other shapes are equally suitable, however, as long as the bumps are rounded, smoothed, and highly polished. Also the bumps should curve back and away from the polishing surface which is defined by the highest 50 points of the bumps. Many variations in design may occur to one having ordinary skill in the art and therefore I intend to be limited only to the appended claims.

I claim:

1. A burnishing tool for use on dental castings comprising a shank portion and a head portion, aligned along a longitudinal axis, said shank portion shaped to fit in a dental handpiece for rotation about said axis, and said head portion formed from a rounded solid steel member having a plurality of flutes arranged generally parallel to said axis about the circumference of said head, said flutes being rounded and smooth.

2. The tool of claim 1 in which the flutes together establish a composite shape similar to a dental cutting bur.
